Des. 228,983
Patented Nov. 6, 1973

228,983

BATTERY TOOTHBRUSH

Wilhelmus Gerardus Elisabeth Janssens, Drachten,
Netherlands, assignor to U.S. Philips Corporation, New
York, N.Y.

Filed Feb. 22, 1972, Ser. No. 228,432

Claims priority, application Netherlands Aug. 30, 1971

Term of patent 14 years

Int. Cl. D4—02

U.S. Cl. D4—15

FIG. 1 is a perspective view of a battery toothbrush showing my new design:

FIG. 2 is a left side elevational view thereof;
FIG. 3 is a right side elevational view thereof;
FIG. 4 is a front elevational view thereof;
FIG. 5 is a rear elevational view thereof;
FIG. 6 is a top plan view;
FIG. 7 is a bottom plan view.

I claim:

The ornamental design for a battery toothbrush, as shown.
